UNITED STATES PATENT OFFICE

GEORGE F. SENTER, OF NEW YORK, N. Y.

JOURNAL-LUBRICATING BOX.

SPECIFICATION forming part of Letters Patent No. 293,614, dated February 12, 1884.

Application filed August 30, 1881. Renewed August 16, 1883. (No model.)

To all whom it may concern:

Be it known that I, GEORGE F. SENTER, of the city, county, and State of New York, have invented a new and useful Improvement in 5 Journal-Lubricating Boxes; and I hereby declare the following to be a full and clear description thereof.

This invention relates to a lubricating-box, or box for containing and applying the lubricant to the journal in a continuous and uniform manner, without the use of waste, wicking, or other capillary conductor, such as is usually employed in car-axle journals and similar bearings.

15 This invention relates, first, to the construction and composition of the lubricating-box; and second, to the method or device for applying the box to the journal, so as to form a continuous contact between the journal and the lubricant.

The invention will be readily understood by reference to the accompanying drawings, of which—

Figure 1 is a longitudinal sectional elevation of the improved lubricating-box, as applied to the journal of a railway-car axle. Fig. 2 is a transverse sectional elevation of the same. Fig. 3 is a front elevation of one car-wheel axle with its wheel and bearing-box and pedestal, and also showing the lubricating-box in place.

The axle A, the bearing-box B, and the pedestal C are such as are in use now or in any-wise adapted to the purpose indicated. These 35 may belong to a railway-car axle, or to any other axle. The lubricating-box D will, however, be made and applied in the form shown and now described. This lubricating-box D, I make hollow, or, in fact, a mere shell, with sides, 40 ends, and bottom, but open at the top or bearing side, and into the cavity or chamber of this box I put the lubricant D', which will preferably be a stiff, heavy grease or paste. This box or shell D, I form of a soft anti-friction material, which may be pressed hard 45 against the journal-bearing without producing any deleterious friction between the parts. The material for this purpose may be any sufficiently firm anti-friction material; but I prefer to use for the purpose a mixture of lead, 50 antimony, and ground plumbago, melted together, and cast in the form required. These

metals may be united in about equal proportions; but this is not a matter of importance. This box I press against the journal-bearing 55 with a steady though yielding pressure by means of the spring E, so as to cause the said box D to constantly contact with the journal, thereby keeping out all dust and dirt from the bearing, and also causing the ends of the box 60 D, which press against the journal, to slowly wear away, thereby permitting the lubricant D' to be brought in constant contact with the journal.

It will be seen that the box D, made of an anti-friction material, and soft enough to easily though slowly wear away, will not add to the frictional resistance on the journal, but in many places will be of sufficient firmness to act as the cap of the journal-box, and at all 70 times will hold the lubricant up to contact with the journal, as the slowly-wearing-away contacting surfaces of the box D will allow the unused lubricant to be constantly set up to and in contact with the journal, the springs E, as before explained, acting to constantly press the box up to the journal. The spring or springs E (there may be one or more of them) will preferably be spiral springs, though any form of spring will of course answer the purpose, 80 and these springs will act against a base-plate, E', so as to constantly press the box D and its contents against the journal. The base-plate E' will rest against the base-plate of the pedestal, or against any suitable stationary or relatively stationary part of the bearing. By this arrangement of the lubricating-box, cotton or other waste or fibrous capillary conductor for the oil or lubricant will be wholly dispensed with. The journal will be almost entirely covered, and thereby dust excluded effectually from the journal, and consequently the wear 90 on the journal and its box will be greatly reduced.

These lubricating-boxes may of course be 95 placed at the bottom of the journal, as in the case of a car-axle, as shown in the drawings, or in any other position which may be required.

Having described my invention, I claim—

1. A hollow lubricating-box adapted to contain a stiff plastic or semi-solid lubricant, provided with a longitudinal opening in the side next the journal, whereby the body or mass of

said lubricant is allowed to contact with the journal, said box being constructed of soft anti-friction metal adapted to wear away with the lubricant, whereby the latter is kept in contact with the journal, substantially as described.

2. In a journal-box, the combination of a hollow lubricating-box adapted to contain a semi-solid lubricant, constructed of soft anti-friction metal, and provided with a longitudinal opening on the side next the journal, a spring for holding said lubricating-box in contact with the journal, and a rest for said spring, substantially as described.

3. The combination of the slotted pedestal 15 C, the bearing-box B, the axle A, the rectangular hollow lubricating-box D, constructed of soft anti-friction metal, and provided with a longitudinal opening in its upper side, the semi-solid lubricant D', contained in said box, 20 the spring E, and plate E', all substantially as described.

GEORGE F. SENTER.
